UNITED STATES PATENT OFFICE.

CALEB H. BOOTH, OF DUBUQUE, IOWA.

ATTACHMENT FOR DREDGE-PUMPS.

SPECIFICATION forming part of Letters Patent No. 317,080, dated May 5, 1885.

Application filed October 9, 1884. (No model.)

To all whom it may concern:

Be it known that I, CALEB H. BOOTH, a citizen of the United States, residing at Dubuque, in the county of Dubuque and State 5 of Iowa, have invented certain new and useful Improvements in Attachments for Dredge-Pumps, of which the following is a full, clear, and exact description, reference being had to the accompanying drawings, which form part 10 of this specification, in which—

Figure 1 represents a sectional view of the end of a suction-pipe with my improvements attached. Fig. 2 is an end elevation of the same. Fig. 3 is a bottom plan view.

15 Similar letters of reference indicate corresponding parts in the several figures.

My invention relates to attachments for dredge-pumps, the object of said attachment being to provide a means for stirring or cutting up the mud, clay, sand, or other material 20 preparatory to its being pumped and of utilizing the force of the flow in the suction to operate a suitable cutter; and my invention consists in the construction, arrangement, and 25 combination of devices, all of which I shall hereinafter fully set forth and claim.

Referring to the drawings, A represents a casting in the form of an elbow, and which is attached to the end of a flexible suction-pipe, 30 a, in the usual manner.

Within a step, b, formed on the inside of the casting A is suitably journaled the upper end of a vertical shaft, C, its lower end being supported in a plate, d, which may be bolted 35 or otherwise firmly secured to the lower end of the casting.

Upon the shaft C, near its lower end, is placed a screw-propeller with two or more blades or fans, e, for the purpose of giving a 40 revolving motion to the cutters.

Beneath the plate d, which supports the lower end of the shaft C, is another plate, D, which is keyed or otherwise secured, so that it may have a movement similar to the rotation 45 of the shaft, and upon this plate D is a series of blades or cutters, E, having their cutting-points arranged in a manner substan-

tially as shown in Fig. 3. These cutters may be secured to the plate by any well-known means; but I prefer the construction shown, 50 in which the threaded reduced ends of the cutters enter perforations in the plate, to which they are firmly secured by nuts. These cutters, as before stated, are for the purpose of cutting and stirring up the loose 55 dirt prior to its entering the suction-pipe, and prevent its clogging the same. Secured in the upper and outer end of the casting A is an eyebolt, g, for engaging a chain or other mechanism to lower or raise the suction-pipe. 60

From the foregoing description it is evident that as soon as the pump (not shown) is started the flow of the current in the suction-pipe acting upon the blades of the propeller causes it to revolve, and with it the cross-plate D with its cutters, which so effectually 65 cut and stir up the material to be pumped that it flows easily through the suction-pipe and into a suitable pump, from whence it may be discharged by any well-known means. 70

Having thus fully described my invention, what I claim as new, and desire to secure by Letters Patent, is—

1. The combination, with the suction-pipe of a dredge-pump, of a series of revolving 75 blades and a propeller operated by the flow of the suction, substantially as described.

2. The combination, with the suction-pipe of a dredge-pump, of a vertical shaft supported in suitable bearings, a propeller upon 8 said shaft to be operated by the flow of the suction, and a plate carrying suitable blades or cutters, substantially as described, and for the purpose set forth.

3. The casting A, vertical shaft C, a propeller upon said shaft, a bearing-plate, d, a plate, D, with blades or cutters secured in the perforations, and a means, as set forth, for raising or lowering the end of the suction-pipe, substantially as herein described. 85

CALEB H. BOOTH.
